COLLAR BAR

Edwin S. Mix, Rochester, N. Y., assignor to
Hickok Manufacturing Company, Inc., Rochester, N. Y., a corporation of New York

Application April 5, 1934, Serial No. 719,208

24 Claims. (Cl. 24—81)

This invention relates to collar bars.

One object of the present invention is to provide an ornamental and attractive collar bar provided with reversely disposed curved levers having clasping portions at their outer ends for clasping cooperation with the bar in a manner such as will permit a swiveling of the collar on the wearer without danger of accidental detachment of the bar from the collar and in which 10 the two points of connection of the clasp with the collar may be readily effected and adjusted to regulate the distance desired between the ends of the outer flap or fold of the collar.

Another object of the invention resides in 15 the provision of a collar bar member and a pair of reversely curved side by side intersecting or crossed levers which are easily finger operated to provide for a ready application or removal of the bar from the collar and which will not cause 20 undue wear on the collar.

A still further object of the invention resides in the provision of a collar bar in which the parts may be readily assembled by the placing together of two sub-assemblies, one sub-assembly 25 being constituted by the bar and the other sub-assembly being constituted of a bracket in which the remaining parts are mounted and by means of which all of the parts except the bar are assembled as a sub-assembly or unitary device 30 which may be kept in stock and which may be applied to the bars when desired and secured thereto in any suitable manner.

It is still further designed to provide a collar bar including a bar and cooperating clasping levers and in which all of the parts except the bar may be readily assembled as a unitary mechanism or sub-assembly to be applied as a unitary device to the bar when desired and thereby 35 facilitating the completion of the finished article under certain predetermined demands.

With these and other objects in view, the invention consists in the construction and novel combination and arrangement of parts herein-after fully described, illustrated in the accompanying drawing and pointed out in the claims hereto appended, it being understood that various changes in the form, proportion and minor details of construction, within the scope of the 45 claims, may be resorted to without departing from the spirit or sacrificing any of the advantages of the invention.

In the drawing:—

Fig. 1 is a perspective view of the invention, illustrating the clasp applied.

Fig. 2 is a rear perspective view of the clasp unapplied.

Fig. 3 is a longitudinal sectional view on the line 3—3 of Fig. 1.

Fig. 4 is a transverse sectional view on the line 4—4 of Fig. 3.

Fig. 5 is a perspective view of one of the operating levers.

Fig. 6 is a side elevation of a particular type of spring employed for urging the clasping levers 10 into cooperating clasping relation with the ends of the bar; and

Fig. 7 is an inverted plan view of the spring.

Referring now more particularly to the accompanying drawing, the reference character 1 indicates a bar which is preferably curved longitudinally, and which is preferably solid and rectangular in cross section but which may be of other shape in cross section, the extreme ends being inclined, as at 2, and the inner faces of 20 the bar being serrated or otherwise roughened adjacent the ends thereof, as indicated at 3. This bar is formed preferably of precious metal or other suitable material and may be plain on its outer surfaces or ornamented in any suitable 25 manner if desired.

A bracket 4 of sheet metal or other suitable material is employed and it is adapted to embrace the bar 1 intermediate the ends of the latter and secured thereto in any suitable manner as 30 by soldering or otherwise. This bracket 4 is illustrated as substantially U-shaped and may have its legs or side portions 5 slightly offset, as at 6 and tapered inwardly to provide spaced ears 7. This bracket may be otherwise formed, if desired, 35 so long as it constitutes means for the pivotal support of two similarly formed reversely arranged curved levers 8 and 9.

The levers 8 and 9 are composed preferably of sheet metal but they may be formed of other 40 suitable material. In any event, these levers 8 and 9 preferably intersect or cross each other intermediate their ends in side by side relation and at the point of intersection they are pivoted in their side by side relation in the aforesaid ears 45 7 of the bracket 4 by means of a suitable pivot pin 10. Each lever is formed to provide or has in its back or rear face a groove 11 for a purpose presently explained and each lever includes an outer clasping arm portion 12 and an inner operating arm portion 13, the outer clasping arm portion terminating in an inwardly directed thickened clasping portion 14 which is preferably 50 serrated or otherwise roughened as shown.

The outer arm portion of said levers 8 and 9 55

with their outer clasping portions 14 are normally urged toward the bar 1 into cooperative clasping relation with the ends of the bar. This is accomplished by means of a peculiarly formed 5 spring A. This spring A consists essentially of a single piece of spring wire formed to provide two reversely curved portions 15 and 16, spaced apart, and connected in their spaced relation by an intermediate curved connecting part 17 to 10 form a passage 18 for the aforesaid pivot pin 10 whereby to movably mount said spring on said pivot pin.

The terminal 19 of the spring A is adapted to fit in the back groove 11 of the lever 8 and the 15 oppositely directed terminal 20 of said spring is adapted to lie in the back groove of the other lever 9 whereby to positively urge the outer ends of the respective levers into cooperative clasping relation with the respective ends of the bar 1. 20 These levers 8 and 9 may be formed of solid metal or of sheet metal or other suitable material.

As illustrated, the thickened outer end 14 of each lever 8-9 is enlarged laterally to one side, as at 21, and enlarged longitudinally, and this 25 enlarged portion on its inner face is convex or curved longitudinally, as at 22, and tapers to a smooth outer end. The curved inner surface 22 is serrated, as at 23, or otherwise roughened to provide for effective clasping relation of the outer 30 ends of the levers with the outer ends of the bar 1, the smooth inner portions of the curved parts at the outer ends of the latter facilitating insertion of the outer flap or fold of the collar between the levers 8 and 9 and the bar 1.

35 The inner end of each lever 8 and 9 is preferably enlarged laterally, as at 26, to broaden the area of the outer end of the levers for finger action by the wearer on the levers to move the levers on the pivot 10 against the tension of the 40 spring A for unclasping purposes.

The bracket 4 may be secured on the bar 1 in any suitable manner, as for instance, by crimping the same on the bar or soldering it to the bar. It is immaterial as to how this connection is 45 made. An essential feature of the invention goes to the employment of a bracket of suitable character in which all of the parts of the device hereinbefore described, except the bar 1, may be assembled together as a sub-assembly or unitary 50 structure to be mounted upon the bar 1 by sliding the bracket onto the bar from one end thereof and securing the bracket in proper position on the bar in any suitable manner. This sub-assembly or unitary structure may be carried in 55 stock in an assembled condition for application to bars of various shapes and forms. In some instances, the body of the bracket may take form other than that herein described and illustrated, but nevertheless, the parts may be assembled as 60 stated ready for application to a bar having a cross section corresponding with the cross section of that part of the bracket which is adapted to be secured to the bar.

65 This is an obvious advantage from a production standpoint and it should be obvious how a bracket carrying the various assembled parts can be placed on the bar from one end thereof and positioned for operative connection with the bar.

70 It will be understood that it is proposed to form the various parts of precious metal, such as gold or silver or to highly ornament the parts in any suitable manner superficially, if desired, which together with gradual curvatures merging one into another and arranged as illustrated to pro-

vide a piece of jewelry which is highly ornamental in character to appeal to the esthetic senses.

It will also be understood that the collar bar herein described and illustrated in the accompanying drawing is light in weight and permits of quite a natural use of the fingers of the right and left hands in applying and adjusting the bar as well as when removing the bar from connection with the collar. The structure is 10 such as to permit a certain amount of swiveling of the collar on the wearer without danger of the bar becoming accidentally detached therefrom, suitable adjustments being possible and readily made by the wearer, quite a range of 15 adjustments being permitted so that the adjacent end edges of the collar may be brought very close together if desired, or in the use of flared collar ends the ends may be readily adjusted to the outermost ends of the bar. 20

The spring A and the arrangement thereof with relation to the pivot pin 10 and the levers 8 and 9, provides for an effective spring action throughout the entire length of the spring on the levers. The pin 10 has a loose mounting in 25 the passage 18 of the spring, permitting of more or less expansion and contraction of the spring lengthwise incident to the pivotal action of the levers on the spring. The curved connecting portion 17 of the spring has rocking movement on 30 the inner face of the bar. The result is a movably mounted spring and a consequent easy fingered pressure operation of the levers 8 and 9 and an effective spring pressed holding of the levers 8 and 9 in cooperative clasping relation with the 35 bar 1. The spring A operates by reason of its shape and floating mounting to respond to various lateral strains or movements of the levers on the pivot 10 incident to finger operation of the levers or due to a swivelling action of the 40 wearer's collar on the bar at the two points thereon.

The roughening of various parts prevents slippage and accidental displacement of the bar with relation to the collar, and while I have referred to serrations for roughening purposes it will be understood that I do not wish to limit the invention necessarily to serrations or roughening of any character or to any particular character of serrations or roughening of the surfaces for equivalent means, such as teeth, protuberances, notches and even depressions might be employed to prevent slippage between various cooperative parts.

It will be understood that the collar bar or 55 holder is of comparatively small size and that it has been illustrated to a somewhat exaggerated extent for the sake of clearness of illustration.

What is claimed is:—

1. An article of manufacture for collar bars or the like comprising a longitudinally curved bar, a bracket secured to the bar intermediate the ends thereof, a pair of curved reversely arranged levers pivoted intermediate their ends on said bracket, and means for urging the outer ends of the levers to clasping cooperation with the respective ends of the bar, said bracket being slidable on the collar bar with the collar bar between the front of said bracket and said urging means to operatively position the bar with respect to the bracket and to enable assembling of the bracket, levers and urging means as a unit for the reception of the desired character of bar. 60

2. An article of manufacture comprising a lon- 75

- 5 gitudinally curved bar, a bracket secured to the bar intermediate the ends thereof, a pair of curved reversely arranged levers pivoted intermediate their ends on said bracket, the outer 5 end of each lever having an inwardly directed portion provided with a clasp- 10 ing cooperation with the adjacent respective end of said bar, and means for urging said outer ends of the levers to clasp- 15 ing cooperation with the respective ends of said bar, said bar being slid- 20 able in said bracket between the front of said bracket and said urging means to operative position with relation to the bracket so that the bracket, levers and urging means may be 25 assembled as a unit for the reception of the desired character of bar.
3. As an article of manufacture, a bracket, a pair of curved levers reversely arranged and pivoted intermediate their ends to said bracket, each 30 lever having a groove in its inner face, and a spring arranged within the bracket and having engagement with the pivotal means of said levers and having terminals engaging in said grooves of the levers.
- 25 4. An article of manufacture comprising a longitudinally curved bar, a bracket secured to the bar intermediate the ends thereof, a pair of curved reversely arranged levers pivoted intermediate their ends on said bracket, and having 35 their outer ends terminating adjacent the respective outer ends of said bar to cooperate therewith for clasp- 40 ing purposes, and means for urging the outer ends of the levers into cooperative clasp- 45 ing relation with the ends of the bar, the inner end of each lever having a lateral offset portion.
5. As an article of manufacture, a bracket, a pair of curved reversely arranged levers pivoted on the bracket, each lever having a longitudinal 40 groove in its inner side, and a spring composed of spring metal and including reversely curved connected spaced portions arranged to embrace the pivot means for said levers and having oppositely directed terminals located in the grooves 45 of the respective levers.
6. An article of the character described, comprising a longitudinally curved bar, a pair of curved reversely arranged levers pivoted on the bar intermediate the ends of the latter and including outer arm portions and inner operating 50 portions, the extremities of the outer ends of the outer arm portions being deflected inwardly toward the ends of the bar for clasp- 55 ing cooperation therewith, and means for urging the outer arm portions of the levers to cooperative clasp- 60 ing relation with the ends of the bar, said bar being slid- 65 able in said bracket between the front of said bracket and said urging means to operative position with relation to the bracket so that the bracket, levers and urging means may be assembled as a unit for the reception of the desired character of bar.
7. An article of the character described, comprising a longitudinally curved bar, a pair of curved reversely arranged levers pivoted on the bar intermediate the ends of the latter and including outer arm portions and inner operating 70 portions, the extremities of the outer ends of the outer arm portions being deflected inwardly toward the ends of the bar for clasp- 75 ing cooperation therewith, and a single spring including reversely curved portions for urging the outer arm portions of the levers to cooperative clasp- 80 ing relation with the ends of the bar.
8. An article of manufacture comprising a bar, a substantially U-shaped bracket secured to the bar and having its side portions offset outwardly intermediate the ends thereof and tapered beyond said offset portions to form spaced ears, a pivot pin extending transversely through said ears, a pair of similarly curved levers reversely arranged and pivoted on said pivot pin and having their outer ends disposed for clasp- 85 ing cooperation with the ends of the bar, and means urging the outer ends of the levers normally in clasp- 90 ing cooperation with the ends of the bar, said bar being slid- 95 able in said bracket between the front of said bracket and said urging means to operative position with relation to the bracket so that the bracket, levers and urging means may be assembled as a unit for the reception of the desired character of bar.
9. An article of the character described comprising a bracket, a pair of similarly formed levers reversely arranged, a pin pivotally securing the levers in said bracket, a spring loosely engaging said pivot pin and including oppositely disposed spaced, reversely curved portions extending longitudinally of said levers and connected together, the connecting portion between the reversely curved portions of said spring being curved and the ends of the spring bearing one end against one lever and the other end bearing against the other lever.
10. An article of the character described comprising a longitudinally curved bar, a bracket secured to the bar intermediate the ends thereof and having spaced ears, reversely curved levers arranged between said ears, a pin extending transversely through the ears and levers to pivotally mount the levers in the bracket, each lever having a longitudinal groove in its face adjacent the bar, and a spring composed of a single piece of spring wire shaped to form reversely curved spaced portions connected together and having their inner ends overlapping in spaced relation to provide spaced seats for said pivot pin and having their outer ends engaging in one or the other of said grooves in the levers, the connecting portion between the reversely curved portions of the spring engaging the inner face of said bar.
11. An article of the character described comprising a longitudinally curved bar, a bracket secured to the bar intermediate the ends thereof and having spaced ears, reversely curved levers arranged between said ears, a pin extending transversely through the ears and levers to pivotally mount the levers in the bracket, each lever having a longitudinal groove in its face adjacent the bar, and a spring composed of a single piece of spring wire shaped to form reversely curved spaced portions connected together and having their inner ends overlapping in spaced relation to provide spaced seats for said pivot pin and having their outer ends engaging in one or the other of said grooves in the levers, the connecting portion between the reversely curved portions of the spring engaging the inner face of said bar, said reversely curved portions of the spring being expandable and contractible lengthwise and longitudinally of the bar with their outer ends slid- 65 able in the grooves of the levers.
12. A device of the character described comprising a bracket, levers extending through the bracket and having longitudinal grooves therein, a pin extending transversely through the bracket to pivot the levers in the bracket, and an expandable and contractible one piece spring including reversely curved portions loosely embracing said 75

pivot pin and having portions engaging slidably in one or the other grooves of said levers.

13. An article of manufacture, a longitudinally curved bar, similarly formed curved levers reversely arranged and pivoted on the bar by means of a pivot pin, the outer ends of the levers terminating opposite the ends of the bar, and means for urging the outer ends of the levers into clasping relation with the ends of the bar consisting of a spring composed of a single piece of spring wire and including laterally spaced reversely curved portions connected by a curved spacing portion, said reversely curved portions of said spring loosely embracing said pivot pin and bearing against the backs of the respective aforesaid levers and the curved connecting portion having movable engagement with the inner face of the bar whereby the spring is movably mounted on said pivot pin and normally exerts pressure throughout its length on said levers.

14. An article of manufacture comprising a bar, a pair of similarly formed reversely arranged levers, a pivot pin connected to the bar intermediate the ends of the latter and on which said levers are mounted, the outer ends of the levers being adapted to cooperate with the ends of the bar to clasp material therebetween, and a spring composed of a single piece of wire and including laterally spaced reversely curved portions connected by a curved spacing portion, said reversely curved portions of said spring forming a passage to loosely receive said pivot pin and the end terminals of the reversely curved portions of the spring bearing against the backs of the respective aforesaid levers and the curved connecting portion of the reversely curved portions of the spring having a rocking movement against the inner face of said bar whereby the spring is movably mounted on said pivot pin and normally exerts pressure throughout its entire length on the levers.

15. An article of the character described comprising a bar, a pair of curved reversely arranged levers pivoted on the bar intermediate the ends of the latter and including outer arm portions and inner operating portions, the extremities of the outer ends of the outer arm portions being disposed adjacent the respective ends of the bar for clasping cooperation therewith, and a single spring including reversely curved portions for urging the outer arm portions of the levers into cooperative clasping relation with the ends of the bar.

16. An article of manufacture, a bar, a pair of similarly formed curved levers pivoted on the bar, each lever having a longitudinal groove in its inner side, and a spring composed of spring metal and including reversely curved connected spaced portions arranged to embrace the pivot means for said levers and having oppositely directed terminals located in the grooves of the respective levers.

17. An article of the character described comprising a curved bar, a pair of levers, a pivot pin to pivotally mount the levers on the bar, said levers having their outer ends arranged for clasping cooperation with the ends of the bar, each lever having a groove therein, and a spring for urging the outer ends of the levers into clasping cooperation with the respective ends of the bar including spaced, reversely curved portions extending longitudinally of the levers and movably embracing said pivot pin and connected in spaced relation by a curved portion of the spring which connecting portion has rocking movement against

the inner face of the bar, the ends of the spring lying in the grooves of the respective levers.

18. An article of the character described comprising a bar, a pair of levers, a pin for pivoting the levers to the bar, and a spring including spaced, connected reversely curved portions extending longitudinally of the bar and loosely embracing the pivot pin, the connecting portion of said reversely curved portions having movable engagement with the inner face of said bar and the ends of said spring bearing against the inner faces of the respective levers to normally force the outer ends of the levers into clasping relation with the ends of the bar.

19. An article of the character described comprising a bar, a pair of levers, a pin for pivoting the levers to the bar, and a spring including spaced, connected reversely curved portions extending longitudinally of the bar and loosely embracing the pivot pin, the connecting portion of said reversely curved portions having movable engagement with the inner face of said bar and the ends of said spring bearing against the inner faces of the respective levers to normally force the outer ends of the levers into clasping relation with the ends of the bar, and thereby exerting pressure throughout its entire length longitudinally of said bar on each lever.

20. An article of the character described comprising a bar, a pair of levers, a pin for pivoting the levers to the bar, and a spring including spaced, connected reversely curved portions extending longitudinally of the bar and loosely embracing the pivot pin, the connecting portion of said reversely curved portions having movable engagement with the inner face of said bar and the ends of said spring bearing against the inner faces of the respective levers to normally force the outer ends of the levers into clasping relation with the ends of the bar, said spring being expansible and contractible lengthwise and exerting pressure on the levers throughout its length.

21. An article of the character described comprising a longitudinally curved bar having spaced ears projecting therefrom, a pair of similarly formed curved levers reversely arranged in side by side relation between said ears, each lever having a longitudinal groove in its inner face, a pivot pin for said levers extending through them and through said ears, a spring composed of a single piece of wire formed to provide spaced reversely curved portions extending longitudinally of the bar and levers and overlapping in spaced relation to permit passage of said pivot pin loosely through said reversely curved portions, said reversely curved portions having a connecting portion which bears normally against the inner face of the bar between said ears, the terminals of the spring extending in opposite directions longitudinally of the bar and located in the grooves of the respective levers whereby the spring exerts pressure throughout its length against each lever.

22. An article of the character described comprising a bar, a pair of similarly formed curved levers reversely arranged in side by side relation and pivotally connected to the bar, a pivot pin for pivoting said levers to the bar, each lever having a longitudinal groove in its inner face, and a spring composed of spaced, reversely curved, resilient portions having a resilient curved connection between them and having their inner ends overlapping in spaced relation to form spaced seats for said pivot pin, and each reversely curved

portion having an outer end portion forming a terminal for engagement in the groove of one or the other of said levers, said curved connecting portion being adapted to movably bear against the inner face of the bar, the said spring being 5 expandible and contractible lengthwise with the outer ends slidable in the grooves of said levers.

23. An article of manufacture comprising a longitudinally curved bar, a bracket embracing the bar intermediate the ends thereof and including 10 portions extending rearwardly of the bar, a pair of similarly formed curved reversely arranged levers pivoted intermediate their ends on said rearwardly extending portions of said bracket, and spring means between said rearwardly extending portions of the bracket and between the back of said bar and the inner faces of said levers and exerting pressure against the bar and the levers to urge the outer ends of the levers to 15 clasping cooperation with the respective ends of the bar, said bar being slid able in said bracket between the front of said bracket and said urging means to operative position with relation to the bracket so that the bracket, levers and urging 20 means

25

means may be assembled as a unit for the reception of the desired character of bar.

24. An article of manufacture comprising a bar, a bracket embracing the bar intermediate the ends thereof and including portions extending on opposite sides of the bar rearwardly of the bar, a pair of similarly formed curved reversely arranged levers pivoted intermediate their ends on said rearwardly extending portions of said bracket and having their outer ends deflected toward the bar for clasping cooperation with the respective ends of the bar, and spring means arranged between said rearwardly extending portions of said bracket and between the back of said bar and the inner faces of said levers to exert 15 pressure against the bar and levers to thereby urge the outer ends of the levers to clasping cooperation with the respective ends of the bar, said bar being slid able in said bracket between the front of said bracket and said urging means to operative position with relation to the bracket so that the bracket, levers and urging means may be assembled as a unit for the reception of the desired character of bar.
